UNITED STATES PATENT OFFICE.

GEORGE W. DAVIS, OF BURNSIDE, PENNSYLVANIA.

WAGON-JACK.

SPECIFICATION forming part of Letters Patent No. 361,813, dated April 26, 1887.

Application filed October 6, 1886. Serial No. 215,468. (No model.)

To all whom it may concern:

Be it known that I, GEORGE W. DAVIS, a citizen of the United States of America, residing at Burnside, in the county of Clearfield 5 and State of Pennsylvania, have invented certain new and useful Improvements in Wagon or Buggy Jacks, of which the following is a specification, reference being had therein to the accompanying drawings.

10 My invention has for its object to provide an improved, novel, and simplified vehicle-jack which will be durable in construction and efficient in its action, combined with ease of manipulation and ready adaptation to the purpose contemplated.

To these ends my improvements consist, essentially, of a vertical support or standard having its upper portion centrally slotted for the reception therein of the one end of a lever, the axis of which is adapted to engage 20 with one of a series of recesses in the side of said support, and said lever being provided upon its upper surface with a ratchet-plate which is adapted for operation in connection with a pivoted pawl in the manner and 25 for the purposes as will be hereinafter fully described, and pointed out in the claim.

In the accompanying drawings, Figure 1 represents a side elevation of my complete invention, and Fig. 2 a detail sectional view thereof.

Similar letters of reference indicate like parts in both figures of the drawings.

In carrying out my invention I provide an upright standard, A, having a suitable supporting-base, A', and strengthening-brace A'', as shown, the upper portion of said standard being centrally slotted, as shown at B, for the reception therein of the one end of the lever C. Upon each side of the slotted portion B is 35 provided a series of recesses, a, the inner ends of which are provided with semicircular bearings a', for the reception of the ends of the axle b of the lever C.

Vertical and overhanging rods D are secured 40 to the front upper part of the standard A, one upon each side of the opening B, the object of

which is to prevent the lever C from being disengaged from the standard, yet permitting of the same being readily raised or lowered in the series of recesses a. Upon the upper surface of the lever C is provided a ratchet-plate, E, with which engages the lower end of the pawl F, the upper end of which is pivoted at G in the upper end of the recess B, as shown. 50

In the operation of my improved device the lever C is adjusted in either of the series of recesses a, according to the height of the vehicle-axle to be raised. Now, by depressing the handle of the said lever, the axle is elevated to the desired point, the pawl F dropping into one of the series of teeth on the ratchet-plate E, according to the depression of the lever, and firmly holding the axle at the desired position for the ready removal or replacement of the wheel during the operation 60 of lubricating the axle.

The construction of my improved vehicle-jack is such that it can be readily adjusted to vehicle-axles of different heights, is easily and quickly manipulated, and occupies but little 65 space when not in use.

Having thus described my invention, I claim as new and useful—

In a wagon-jack, the standard A, having a base-block and a connecting metal brace, said standard being vertically slotted, the side walls horizontally recessed inward with undercut rounded bearings, a guard-loop secured in front of said recesses, and a curved flat pawl pivoted at the top within the slot, in combination 75 with a lever working in the slot and having a ratchet-plate on its upper surface, and a rigid cross pivot-pin adapted to enter opposite recesses and loosely fit in the undercut portion of said slot, substantially as shown and described. 80

In testimony whereof I affix my signature in presence of two witnesses.

GEORGE W. DAVIS.
